SIDNEY W. MIMS, OF LOS ANGELES, CALIFORNIA.

METHOD AND MEANS FOR PERFORATING WELL CASINGS.

Application filed March 3, 1924. Serial No. 696,454.

To all whom it may concern:

Be it known that I, SIDNEY W. MIMS, a citizen of the United States, residing at Los Angeles, in the county of Los Angeles and State of California, have invented a new and useful Method and Means for Perforating Well Casings, of which the following is a specification.

This invention relates to a method and means for perforating well casing and refers particularly to a method and means for perforating well casing in place in a well hole.

In the construction and operation of oil wells it frequently becomes necessary to perforate a pipe or casing in place in the well hole and disposed at a considerable distance from the top of the well hole. The art has found considerable difficulty in properly opening such well casing or pipe. One example of the necessity of opening such holes is encountered where a casing has been cemented in a well hole for the purpose of shutting off the water from the oil sand and it is then found that the shut off of water is not complete and it is desired to open the casing at another point to permit further cement to be forced behind the well casing so as to complete the shut off. Moreover, in certain oil fields the oil wells have been originally drilled to upper oil sand which at the start of the history of the oil field produced less oil than the lower oil sand and accordingly a great number of wells have been drilled through the first oil sand, the well pipe then cemented to close up the well formation, and the well then bored below such upper oil sand into the lower oil sand with an additional casing employed for reaching to the lower oil sand.

As the lower sand becomes exhausted it is desirable to again open the well into the upper oil sand, and for this purpose it is necessary to perforate both well casings at the same time.

An object of this invention is to provide an improved device for perforating well casings and to provide such a device as will form a clean hole through the well pipe leaving the pipe or casing undamaged and strong around the perforations and to provide such a method and means as can be used to perforate even double the wall casing in place in a deep well.

Other objects and advantages of the invention will be apparent from the descrip-

tion of the invention in its preferred form or embodiment.

Reference is therefore had to the accompanying drawings, which illustrate a device which may be used to carry out my preferred method of perforating a well pipe or casing in place in an oil well.

Figure 1 is an elevation in vertical section through a well hole disclosing the manner of perforating a well pipe or casing in order to re-cement the well.

Fig. 2 is an enlarged elevation mainly in vertical section of the body of the perforating device shown in Fig. 1.

Fig. 3 is an end elevation of a modified form of the device.

Fig. 4 is an elevation at right angles to Fig. 3 and mainly in vertical section.

Fig. 5 discloses another sectional view of a well hole in this case illustrating the double wall casing which may be perforated by the device and method of a further modification of this invention.

Fig. 6 is an enlarged view of this further modification of the perforating device mainly in vertical section.

Referring first to Fig. 1, the 1 indicates a well casing or pipe in place in a well hole, which pipe has previously been cemented so that cement indicated at 2 lies outside of the well casing 1, between the casing and the formation 3. In such a well hole the small passages such as 4 may open up between the cement 2 and well casing 1. By my invention such passages 4 may be sealed up by first perforating the pipe 1 by a perforating device 5 and then forcing cement through the perforations produced to seal such passages 4.

In Fig. 2 the perforating device is shown in one of its preferred forms, such perforating device comprising a body 6 of steel or other metal having a chamber 7 in its center. 8 indicates a number of lateral ways extending from the outside of the body 6 to the center of the chamber 7 which receive slugs 9 of a size to closely fit the ways 8 and preferably provided with pointed ends 10 fastening the outside of the body 6. The slugs 9 extend a distance within the chamber 7 and there engage anvils 11 shaped to fit the chamber 7 and slide therein, said anvils 11 being normally held by the slugs 9 a distance from the side walls of the chamber 7 and being spaced

apart to provide a central explosive chamber 12.

The central explosive chamber 12 is filled with an explosive material 13 such as trinitrotoluene or blasting gelatine and has embedded therein a detonating cap 14, the cap 14 being provided with electrical means 15 by which the cap can be exploded from the top of the well. The body 6 is provided 10 with a vertical bore 16 extending upwardly from the center of the chamber 7 by which the explosive charge may be inserted into the space between the anvils 11, and a plug 17 is threaded into the bore 16 to close the 15 opening and also to provide a handle 18 by which the device may be raised and lowered within the well casing 1. Ducts 19 are also provided in the body 6 leading from the outside to a point normally closed by the anvils 11 but adapted to be uncovered when the anvils 11 are forced to the side walls of the 20 chamber 7.

When employing this form of the invention the body and parts carried thereby are 25 lowered upon a line, such as 20, down to the position within the well hole where the perforations are to be made. The cap 14 is then exploded by means of an electrical lead 15 which causes an explosion of the main 30 charge between the anvils 11. The explosion of such charge throws the anvils 11 to the side walls of the chamber 7, the anvils 11 thus shoot the slugs 9 from the body of the perforating device which then pass through 35 the well casing 1 leaving a clean form of perforation therein. The body 6 is of course made of sufficient strength to resist the force of the explosive charge 13. The anvils 11 arriving at the sides of the chamber 7 open 40 the ducts 19 so as to permit an escape of the gases through such ducts.

In the form of the invention shown in Figs. 3 and 4 the perforating device comprises 45 a body 21 having a groove 22 therearound which receives a strap 23 to which a line may be attached for raising and lowering the body 21 within the well hole. The body 21 is bored out as indicated at 24 from one 50 side thereof to provide a chamber for holding an explosive charge and directing the force of the explosive laterally from the perforating device and against a well casing, the explosive 25 either entirely filling the bore or filling the inner end of the bore, the outer 55 end being closed by a slug 26 having a pointed end 27. Near the end of the bore 24 a detonating cap 28 is imbedded in the explosive 25 and connected to wires 29 leading through a vertical passage 30 to the top of the well. 60 The vertical passage 30 communicates with the bore 24 and receives a plug 31 closing the passage, packing material 32 preferably being positioned between the plug 31 and the explosive charge 25.

65. This embodiment of the invention differs

from the preceding method as it eliminates the anvils 11 which are not necessary to all forms of the invention and moreover has a uniform bore chamber 24 and may, if desired, dispense with the use of the slug 26. 70 The slug 26 may be eliminated, since the force of the explosive charge is so confined by the body 21 and directed to the discharge from said body, that when such slug 26 is eliminated the force of the explosive charge 75 is directed against the casing and perforates the same by burning therethrough, as will be more fully pointed out in connection with the embodiment illustrated in Fig. 6.

The form of the invention shown in Fig. 80 6 has an inverted T-shaped body 32, the lower end of which is provided with a bore 33 extending from end to end of the body and the upper portion being provided with a bore 34 communicating with the bore 33 and enlarged at its upper end as indicated at 35 to receive a plug 36. The smaller end of the bore 34 receives a casing 37 closely fitting the bore 34 and holding a detonating cap 38, the cap 38 being connected with electrical leads 39 by which it may be fired. The lower bore 33 is preferably filled from end to end with an explosive charge. This form of the invention is preferable when dispensing 85 with the slug. The detonation of the cap 38 will cause the explosive in the bore 33 to perforate a well pipe by burning through the pipe as the body 32 is made of sufficient strength to resist the force of the explosive, and hence the explosive concentrates 90 its force upon points opposite the ends of the bore 33 with the result that even a double wall casing such as indicated at 95 35 may be burned through.

100 While I have described the invention in its preferred form, it is understood that I do not desire to be limited to the preferred form of the invention as shown herein, and various modifications may be made without departing from the spirit of the invention, 110 and the invention is of the scope set forth in the appended claims.

I claim:

1. The method of perforating a well casing 115 in place in a well hole, which comprises lowering an explosive charge down the well casing inside of a body of sufficient strength to resist the explosion of the charge and having openings for directing the force of the explosion out against the well casing, and then firing the charge in place in the well hole.

2. A method of perforating a well casing 120 in place in a well hole, which comprises lowering an explosive charge down the well casing, exploding the charge, and directing the force of the charge in the direction of the well casing and thereby perforating the same.

3. A device for perforating a well casing 125

in place within a well hole, which device comprises a body, an explosive charge within the body, said body having means for directing the force of the explosive against a well casing, and being of sufficient strength to resist the destructive force of said charge, and means for detonating the charge when lowered down in a well hole.

4. In a device for perforating a well casing in place in a well hole, the combination of an explosive charge, a body holding the explosive charge, said body being sufficiently strong to resist the force of the explosive charge, lateral ways for directing the force of the explosive towards the well casing, slugs normally closing the ways, and means for detonating the explosive in place in a well hole.

5. A device for perforating a well casing when in place in a well hole, which device comprises in combination a metal body adapted for holding an explosive charge,

said body being of the requisite thickness to resist the force of the explosive and having ways for directing the force of the explosive laterally against the well casing, slugs normally closing the ways, anvils between the slugs and explosive, and means for detonating the explosive in place within the well hole.

30

6. A device for perforating a well casing when in place in the well hole, comprising a body adapted to hold an explosive charge, said body being lowerable within the well casing, and having means for directing the force of the explosive against such well casing when suspended therein, the body being of sufficient strength to resist the destructive force of said charge, and means for suspending and detonating the charge in place in a well hole.

Signed at Los Angeles, California, this 25th day of February, 1924.

SIDNEY W. MIMS.
